NO. 11,809

JUNE 8, 1880

UNITED STATES PATENT OFFICE.

RODOLPHE CHRISTESEN, OF NEW BRITAIN, CONN., ASSIGNOR TO THE RUSSELL & ERWIN MANUFACTURING COMPANY, OF SAME PLACE.

DESIGN FOR CHANDELIER-HOOK.

SPECIFICATION forming part of Design No. 11,809, dated June 8, 1880.

Application filed May 8, 1880. Term of patent 7 years.

To all whom it may concern:

Be it known that I, RODOLPHE CHRISTESEN, of the city of New Britain, and county of Hartford, and State of Connecticut, have invented 5 a new and useful Design for Chandelier-Hooks; and I do hereby declare that the following specification, taken in connection with the accompanying illustration, forming a part of the same, is a full, clear, and exact description 10 thereof.

The design hereinafter described is adapted to that variety of screw-hooks known as "chandelier hooks," and it consists of the following features:

15 At the head of the screw A is a disk, B, whose under surface is ornamented by geomet-

rical flowers and buds b b'. From this disk depends a hook, C, with nearly straight sides c c' and curved portions c² c³ c⁴. Surrounding the edges of the flat sides of the hook is a plain 20 raised border, d, which terminates at the point of the hook in a geometrical flower. Each side is ornamented by an Egyptian head, D, bars E e, and rosettes F.

What I claim, and desire to secure by Letters Patent, is—

The design for chandelier-hooks, substantially as described and shown.

RODOLPHE CHRISTESEN.
